CONCRETE MIXER.
APPLICATION FILED JUNE 27, 1907.

2 SHEETS—SHEET 2.

UNITED STATES PATENT OFFICE.

PHILIP A. KOEHRING, OF MILWAUKEE, WISCONSIN.

CONCRETE-MIXER.

No. 884,667

Specification of Letters Patent.

Patented April 14, 1908.

Application filed June 27, 1907. Serial No. 381,008.

To all whom it may concern:

Be it known that I, PHILIP A. KOEHRING, a citizen of the United States, residing at Milwaukee, county of Milwaukee, and State 5 of Wisconsin, have invented new and useful Improvements in Concrete-Mixers, of which the following is a specification.

My invention relates to improvements in that class of concrete mixers in which cement, sand and other materials composing the concrete are mixed together within a revoluble drum, and it pertains to the means employed for discharging the concrete from the rotating drum at the will of the operator.

15 The object of my invention is to provide a rotary mixing drum having means for discharging the contents, with a manually adjustable device whereby the discharging means may be rendered inoperative at will 20 although continuously actuated, the drum being thus caused to alternately mix the material and discharge the same while being continuously rotated.

Figure 1 is a side view partly broken away 25 to show the interior of the drum and the discharging apparatus. Fig. 2 is a detail end view of the discharge apparatus. Fig. 3 is a plan view of the drum and its discharge apparatus.

30 Like parts are identified by the same reference figures throughout the several views.

1 represents the drum, which is revolvably supported from the frame 2 of the vehicle through the rollers, 3, 3, and roller supporting brackets 4. Motion is communicated to the drum 1 from the sprocket chain 5 through the sprocket wheel 6, wheel supporting shaft 7, pinions 8, 8, and two annular series of cog teeth, 9, 9, which series of 40 teeth, 9, 9, are secured to the periphery of the drum. The shaft 7 is supported from the frame at its respective ends by the brackets 10, 10. The mechanism thus far described is substantially of ordinary construction. A U-shaped trough 12 is rigidly mounted upon the frame work 2 by means of vertically disposed angle iron standards, 13, 13, and horizontally disposed bars 14, 14, secured thereto by rivets 14' in the usual 45 manner. The trough 12 extends into the open end 15 of the drum, and is adapted to receive the material which is elevated and discharged into the receiving end of the trough by bucket flanges 31 on the inner 50 surface of the drum. The trough is preferably horizontally disposed and the material

is pushed to the discharge end by conveyer flights or blades 31 on a shaft 16 mounted in bearing brackets 17 and 18 connected with the trough and frame respectively. Motion 60 is communicated to the shaft 16 from the shaft 7 by means of a sprocket wheel 19, chain 20 and sprocket wheel 21.

An A-shaped hood or covering 33 is mounted upon the axially extending supporting bars 14 within the drum, and is adapted to be adjusted to cover and uncover the receiving end of the trough 12. When in the position in which it is shown in Fig. 1, the trough is uncovered and receives the material discharged in that direction by the bucket flanges 31. When moved to the position indicated by dotted lines in Fig. 1, the receiving end of the trough is covered and the material from the buckets falls to the 70 bottom of the drum, being subdivided by the hood 33 which facilitates the mixing operation. The hood is adjusted along the bars 14 by means of a rod 35 and handle 36. The conveyer blades remove the material received by the trough by pushing it outwardly to the discharge end.

It is obvious that with my discharge apparatus, a quantity of the concrete may be first mixed and then discharged from the 85 drum without interrupting its continuous rotation, the mixing and discharging operations being controlled by the hood 33.

22 is a hopper through which the materials to be mixed are fed into the drum at its receiving end while the same is being rotated. The hopper 22 is supported from the supporting frame of the vehicle upon the standards 13 with which standards it is connected by rivets 23 in the ordinary manner.

The frame 2 upon which the drum 1 is mounted is preferably supported on a wheeled vehicle of ordinary construction by which the machine is readily transported from one place to another.

It will be understood that the concrete in the drum is mixed dry. Water is supplied to it during its discharge, from a pipe 40 provided with spraying perforations 41 and a valve 42 controlling the flow of water to this pipe from a supply pipe 43. The water is cut off from the pipe 40 during the mixing operation, which continues until a supply of concrete is desired, whereupon the hood is moved back to the position in which it is shown in Fig. 1 and the valve 41 opened. The concrete will then be delivered from the

drum and moistened from the pipe 41 until the hood is returned to the dotted line position of Fig. 1, when the water will also be again shut off and the mixing operation with-
5 out delivery will be resumed.

Having thus described my invention what I claim as new and desire to secure by Letters Patent is,

1. In a concrete mixer of the class de-
10 scribed, the combination of a revoluble drum provided on its inner walls with an annular series of elevating and mixing buckets, means for delivering the ingredients into said drum, a discharge trough having a receiving end 15 extended within said drum, a slidable hood adapted to cover the receiving end of said trough, means for shifting said hood into and out of covering position whereby the contents of said drum may at the will of the operator be caused to fall into the receiving end of said trough or back into the lower portion of the drum.
2. In a concrete mixer of the class de-
25 scribed, the combination of a revoluble drum provided on its inner walls with an annular series of elevating and mixing buckets, means for delivering the ingredients into said drum, a discharge trough having a receiving end ex-
30 tended within said drum, a slidable hood adapted to cover the receiving end of said trough, means for shifting said hood into and out of covering position whereby the contents of said drum may at the will of the operator be caused to fall into the receiving end
35 of said trough or back into the lower portion of the drum, and a conveyer for discharging the concrete from said trough.
3. In a concrete mixer of the class de-
40 scribed, the combination of a revoluble drum provided on its inner walls with an annular series of elevating and mixing buckets, means

for delivering the ingredients into said drum, a discharge trough having a receiving end ex-
45 tended within said drum, a slidable hood adapted to cover the receiving end of said trough, means for shifting said hood into and out of covering position whereby the contents of said drum may at the will of the operator be caused to fall into the receiving end of said trough or back into the lower portion 50 of the drum, and a conveyer for discharging the concrete from said trough consisting of a centrally disposed rotary shaft suitably journaled in bearings and having a spiral series of propeller blades radially mounted 55 thereon.

4. In a concrete mixer of the class de-
scribed, the combination of a revoluble mixing and elevating device, a receiver for the elevated material and an adjustable hood 60 therefor adapted to be moved to cover or uncover the receiver, said hood being arranged to return the material falling thereon into the lower portion of the mixing device.

5. In a concrete mixer of the class de-
65 scribed, the combination of a revoluble mixing and elevating device, a receiver for the elevated material and an adjustable hood therefor adapted to be moved to cover or uncover the receiver, said hood being ar-
70 ranged to return the material falling thereon into the lower portion of the mixing device, together with means for delivering water into the material during its delivery from the mixing device. 75

In testimony whereof I affix my signature in the presence of two witnesses.

PHILIP A. KOEHRING.
